UNITED STATES PATENT OFFICE.

BERTHOLD A. LANGE, OF ST. LOUIS, MISSOURI.

EGG CASE.

Application filed November 24, 1922. Serial No. 602,974.

To all whom it may concern:

Be it known that I, BERTHOLD A. LANGE, a citizen of the United States, residing at the city of St. Louis, in the State of Missouri, have invented certain new and useful improvements in Egg Cases, of which the following is a specification.

The transportation of eggs is one of the largest and most difficult phases of commerce. The value of the egg and its fragility combine to make any saving of breakage of extreme economic importance. Many kinds of egg-cases or crates have been tried, but all possess some defect or another. The construction herein shown and described is one of the best for protecting the eggs from breakage, and the specific object of this invention is to make the egg-crate less flimsy and to stiffen or stabilize the same. Another specific object of this invention is to embody in the case or filler itself a substitute for the loose diaphragm commonly inserted between egg-crates.

In the accompanying drawings forming part of this specification, in which like numbers of reference denote like parts wherever they occur,

Figure 1 is a perspective view of a tier composed of two of these devices; and

Figure 2 is a sectional view of a modification or alternative form.

A box 1 may or may not be used to inclose the fillers embodying this invention. The fillers may be arranged in a plurality of as many tiers as desired or may be used singly.

Each filler comprises a plurality of flexible strips 2, arranged at substantially a rightangle to a plurality of flexible strips 3, the same being preferably interlocked, which may be by any suitable means, such for instance (as shown in the drawing) as there being slits 4 and 5 in the strips 2 and 3, faced oppositely to each other and overlapping the opposing strip. Notches 6 in strips 2 and 3 receive the part of the opposing strip not cut away.

Instead of the usual diaphragm between tiers of eggs each row of pockets 7 is provided with a lid 8, which can be used for the said purpose as the said diaphragm, namely a floor upon which the eggs in the upper pockets can rest.

When it is desired to remove a crate composed of a plurality of strips 2 and 3 it is merely lifted and the eggs remain each upon

its underlying lid 8 until removed by hand or otherwise. It is thus unnecessary to pick each individual egg out of its pocket 7.

In practice hitherto it has been observed that the diaphragms between crates or tiers do not in anywise stiffen the same and such crates are flexible and flimsy and easily collapsible by force exerted from any direction. This tends to breakage of the eggs.

The lids 8 stiffen the structure, and especially when bearing a superimposed weight or held by friction render the crate as stiff as need be and uncollapsible by side thrust or ordinary pressure.

The strips 2 and 3 form partitions and side walls, and their ends terminate in projections 9. The lids 8 project so as to overlie the said projections 9 and thus to protect the same from being bent or broken. When they are bent or broken the breakage of eggs in the crate is increased.

In Figure 1 the partition 10 is shown composed of double strips 2, with the lids 8 springing therefrom turned to the right and to the left. The next partition 2 to the right bears a lid 8 turned to the right, while the next partition 2 to the left bears a lid turned to the left. This arrangement is carried on to both the right and the left to form as many pockets 7 as may be desired. This is a neat and economical arrangement. An alternative form is, however, illustrated in Figure 2, in which the lids 8 of the outside partitions 2 bear lids 8 turning inwardly. The other lids 8 may be turned either to the right or to the left.

The lids 8 may be formed integral with the partitions 2 or attached thereto by any suitable means, but in the drawings they are shown integrally connected with the strips or partitions 2. In the form shown in Figure 2 the bend 11 forms a hanger for the two outside lids 8.

This egg-crate filler is adapted to be collapsed for shipment or reshipment and thus to occupy very little space; but when filled with eggs in its pockets the stiffening strips maintain it in a condition not readily to be collapsed or caused to yield or bend under ordinary pressure.

The stiffening strip or strips may be on either the top or the bottom of the egg-case or partially on top and partially on the bottom.

Having thus described this invention, I

hereby reserve the benefit of all changes in form, arrangement, order, or use of parts, as it is evident that many minor changes may be made therein without departing from the spirit of this invention or the scope of the following claims.

I claim:

1. An egg-crate filler formed of flexible strips arranged transversely of each other so as to form pockets and each of the strips extending in one direction only carrying a strip extension forming a lid for each individual row of pockets and a floor on the superposed row of pockets.
10. 2. An egg-crate filler formed of strips of cardboard or the like arranged at substantially a right angle to each other and provided with interlocking means and having marginal projections and each of the strips extending in one direction carrying a lid overlying the said projections and constituting a floor for the superposed filler.
15. 3. An egg-crate filler composed of strips of flexible material arranged transversely with relation to each other and so notched as to interlock, and a plurality of stiffening strips forming lids for the spaces between

the strips and floors for the spaces between the strips of the superposed filler terminating in proximity of the partition strips and adjacent stiffening strip.

4. An egg-crate filler composed of strips of flexible material arranged transversely with relation to each other and so notched as to interlock, and a plurality of stiffening strips forming lids for the spaces between the strips and floors for the spaces between the strips of the superposed filler, the said first-mentioned strips forming marginal projections and the said stiffening strips overlying the same.

5. A cellular filler for egg-crates including a vertical partition-strip constituting a cell wall having one longitudinal edge directed laterally of the open top of the cell and then return bent upon itself and extended in an opposite direction to and beyond the vertical portion of said strip to form a lid for the open top of the cell and a floor for the adjacent portion of the superposed filler.

In testimony whereof I hereunto affix my signature.

BERTHOLD A. LANGE.
